RAZOR BLADE HOLDER

Edwin F. Hardey, Kansas City, Mo.

Application November 12, 1949, Serial No. 126,860

4 Claims. (Cl. 51—218)

1

This invention relates to a device for retaining and supporting a safety razor blade with the cutting edges in position for stropping and/or honing and has for its principal object to provide a device of this character that is of simple and inexpensive construction.

Other objects of the invention are to provide a blade support which is easily and accurately operated, to provide a blade support which imparts the curvature in a double-edged blade that is necessary to bring the beveled faces which form one side of the respective cutting edges into a common plane for simultaneously conditioning one side of both edges, and to provide a supporting device which securely retains the blade from shifting out of position and which does not require separate clamping devices.

In accomplishing these and other objects of the invention I have provided improved structure, the preferred form of which is illustrated in the accompanying drawing wherein:

Fig. 1 is a perspective view of a razor blade retaining and supporting device for conditioning the cutting edges of a double-edged blade and embodying the features of the present invention.

Fig. 2 is a central, longitudinal section through the device.

Fig. 3 is a cross section on the line 3—3 of Fig. 2.

Fig. 4 is a perspective view illustrating the method of using the device in holding the razor blade in position for conditioning the edges thereof.

Fig. 5 is an enlarged, transverse section through the blade supporting device and a razor blade supported thereby, particularly illustrating the curvature imparted therein to bring the bevel faces on one side of the blade into position to be conditioned by a hone or stropping device.

Referring more in detail to the drawings:

1 designates a razor blade supporting and retaining device constructed in accordance with the present invention and which is particularly adapted for thin, flexible blades 2 having normally flat faces 3 and 4 beveled on the edges as at 5, 6, 7 and 8 to provide parallel cutting edges 9 and 10. The ends of such blades are usually provided with tonguelike extensions 11 and 12 that are of less width than the blade to provide shoulders 13—14 and 15—16 at the ends of the cutting edges 9 and 10. The device 1 includes a platelike body portion 17 that is formed of sheet material and has parallel side edges 18 and 19 adapted to extend along and support the cutting edges of the

2

blade, as later described. The body portion is curved transversely to provide a concave blade supporting surface 20 which extends longitudinally of the body portion and has the curvature necessary to support the beveled faces at opposite side edges 5—7 or 6—8 of the blade in coplanar relation. The body portion of the device is of longer length than the blade to provide a straplike anchoring portion 21 that extends transversely and has a lower face 22 spaced upwardly from the curved surface 20 by offsets 23 and 24, a distance substantially corresponding to the thickness of the blade. Extending along the portion 21 is a flange 25 that is turned upwardly from the metal of the body portion to provide a slotlike opening 26 into which one of the tonguelike extensions of the blade is inserted when it is to be moved under the anchoring portion 21.

20 To facilitate entrance of the tongue of the blade and to increase the contact pressure therewith, the anchoring portion is preferably inclined downwardly from the slot toward the end of the body portion, as shown in Figs. 1 and 2.

25 The anchoring portion is also curved transversely substantially conforming to the curvature of the body portion of the holder. The offsets 23 and 24 are spaced apart a sufficient distance to permit ready insertion of a tongue of the blade therebetween and engage the shoulders with ends 27 and 28 of the offsets.

30 The opposite end of the body portion terminates in a neck 29 having substantially the width of the tongue at the opposite end of the blade and which connects with a finger gripping portion 30 by means of an angular offset 31.

35 Turning upwardly from the plane of the body portion on the respective sides of the neck portion 29 are ears 32 and 33 that are spaced apart to pass the tongue of the blade therethrough and to engage the shoulders at that end of the blade, so that the blade is anchored against longitudinal movement when pressure is applied to the upper face of the blade to move it into contact with supporting face of the holder. The finger grip portion may be suitably rounded at the outer corners thereof, as indicated at 34, and may be wider than the neck portion to provide the desired grip, in which case the edges 35

40 50 join with the neck portion in converging edges 36.

In using the holder, the gripping portion 30 is engaged between the thumb and finger of the left hand while the blade is being inserted with the right hand with, for example, the tongue 12 thereon passing angularly through the slotlike

opening 26 until the shoulders 15 and 16 engage against the ends 27 and 28 of the offsets 23 and 24. The blade is then moved toward the supporting surface 20 with the shoulders 15 and 16 of the blade pivoting against the end faces 27 and 28, until the upper face of the tongue 12 engages the under face 22 of the anchoring portion 21 of the holder. In this position, the outer portions of the shoulders 15 and 16, that is, those portions adjacent the ends of the cutting edges 9 and 10, are contacting the marginal sides of the body portion of the holder. The thumb of the left hand is then shifted to engage the upper face of the opposite tongue 11 of the blade to move the tongue downwardly against the curved surface of the neck portion 29. During this movement of the blade, the bearing portions of the blade shoulders at the opposite end effect a curvature in that end of the blade which as the blade moves downwardly continues toward the tongue 11 which has been engaged by the thumb of the left hand. As the shoulders 13 and 14 of the blade pass the ears or stops 32 and 33, the blade is stopped from shifting away from the stop portions 27 and 28. In this position, the flat upper bevel faces 5 and 7 of the blade are in a common plane and in position so that a honing device 31 which may be in the form of a small stone, as shown, can be moved flatwise along the length or crosswise of the blade to sharpen and condition the edges thereof. After using the hone, a stropping device (not shown) may be similarly rubbed along the length of the blade to effect stropping of the edges.

After conditioning the edges at one side of the blade, the pressure of the thumb is released on the tongue 11 and the normal spring action of the blade tending to restore the flat condition thereof automatically raises that end of the blade upwardly from the supporting surface and above the stop ears 32 and 33 whereby the tongue 12 at the opposite end of the blade is readily withdrawn from the slot 26 after which the blade is turned over so that the opposite side is in position to be engaged by the supporting surface of the holder. The blade is again moved into curved condition, as previously described, and the honing or stropping device is used in like manner on the beveled edges 6 and 8 that are then presented and retained in a position to be properly engaged by the conditioning instrument.

From the foregoing, it is obvious that I have provided a simple and inexpensive device by which a blade is supported in proper position to permit honing and/or stropping of the edges thereof so that the common two-edged blade may be reconditioned and kept in such condition that many shaves may be obtained from a single blade.

What I claim and desire to secure by Letters Patent is:

1. A device for holding a relatively thin flexible double edge razor blade having tongue-like extensions at opposite ends comprising a blade supporting member having a transversely curving blade supporting surface and a transverse slot-like opening at one end of said blade supporting member adapted to pass the tongue-like extension at one end of the blade, said blade supporting member having a portion extending transversely with said opening and spaced above said curved supporting surface for pressing against the tongue-like extension at that end of the blade and having a tongue engaging portion at the opposite end of said blade supporting

member adapted to be engaged by the other tongue-like extension of the blade when the blade is pivoted into contact with said supporting surface and said other tongue-like extension is pressed against said tongue engaging portion for imparting curvature in the blade to bring the cutting edges at the respective sides of the blade into a substantially common plane.

2. A device for holding a relatively thin flexible double edge razor blade having tongue-like extensions at opposite ends comprising a blade supporting member having a transversely curving blade supporting surface and a transverse slot-like opening inset from one end of said member adapted to pass therethrough the tongue-like extension at one end of the blade, said end of the blade supporting member having the slot being offset upwardly from and curved in accordance with said supporting surface, a finger grip at the opposite end of the blade supporting member and connected thereto by a neck portion for engaging the other tongue-like extension, and ears disposed at opposite sides of the neck portion to guide said other tongue-like extension therebetween when said other tongue-like extension is pressed into contact with said neck portion to cooperate with said offset portion in retaining the blade in alignment with the blade supporting member and to impart curvature in the blade for bringing the cutting edges at respective sides of the blade into a substantially common plane.

3. A device for holding a relatively thin flexible double edge razor blade having tongue-like extensions at opposite ends comprising a blade supporting member having a transversely concave blade supporting surface and a transverse slot-like opening at one end of said member adapted to pass the tongue-like extension at one end of the blade, said end of the blade supporting member having a part offset upwardly from said supporting surface and adapted to be engaged by said tongue-like extension, a finger grip at the opposite end of the supporting member and connected thereto by a neck portion adapted to be engaged with the other tongue-like extension of the blade, and ears disposed at opposite sides of the neck portion to guide the other tongue-like extension into contact with neck portion when the blade is pivoted into contact with said supporting surface to bring said first named tongue-like extension under said offset portion and said other tongue-like extension of the blade against said neck portion for curving the blade sufficiently for bringing the cutting edges at the respective sides of the blade into a substantially common plane.

4. A device for holding a relatively thin flexible double edge razor blade having tongue-like extensions at opposite ends and provided with spaced shoulders at opposite sides of the tongue-like extensions at ends of cutting edges of the blade comprising a blade supporting member having a transversely curving blade supporting surface and a transverse slot-like opening inset from one end of said member adapted to pass the tongue-like extension at one end of the blade, said end of the blade supporting member having the slot being offset upwardly from said supporting surface for forming stop engaging faces for the shoulders at that end of the blade and having said offset portion curved corresponding to the curvature of the blade supporting surface, a finger grip connected with the opposite end of the supporting member by a neck portion adapted to

be engaged by the other tongue-like extension of the blade, and ears disposed at opposite sides of the neck portion to guide said other tongue-like extension therebetween and engage the shoulders at that end of the blade when the blade is pivoted into contact with said supporting surface to bring said first-named tongue-like extension under said offset portion and said other tongue-like extension against the neck portion to impart curvature in the blade for bringing the cutting edges at respective sides of the blade into a substantially common plane.
